Attorney.

UNITED STATES PATENT OFFICE.

KAREL FREDERIK HENNEMAN, OF THE HAGUE, NETHERLANDS, ASSIGNOR OF ONE-HALF TO PIETER KERKHOVEN, OF THE HAGUE, NETHERLANDS.

ELECTRIC HEATING APPARATUS FOR LIQUIDS.

Application filed August 14, 1924. Serial No. 732,116.

To all whom it may concern:

Be it known that I, KAREL FREDERIK HENNEMAN, a subject of the Queen of the Netherlands, and residing at The Hague, 5 Netherlands, Atjehstraat 69, have invented certain new and useful Improvements in and Relating to an Electric Heating Apparatus for Liquids, of which the following is a specification.

10 The invention relates to an electric heating apparatus for liquids.

The apparatus as such may be arranged in a water conduit or the like with connections to dry-cocks or it may be connected to the switching device of the same inventors in accordance with United States patent application Serial No. 673,211, in which latter case the greatest efficiency will be obtained.

20 The object of the invention is to provide an apparatus wherein by a small consumption of current the liquid may quickly be raised to the desired temperature whilst the use of the connection is at the same time 25 quite safe.

With the apparatus hitherto generally used, the heating winding is arranged in an insulating heat-conducting cover or the wire of the winding is surrounded by a coating.

30 The heat radiated by the glowing wire is therefore not directly communicated to the liquid but only through the insulating coating, with the result, that the liquid comes to the desired temperature less quickly.

35 Further apparatuses are known wherein an electrically heated wire is directly immersed in the liquid so that all heat developed is absorbed by the liquid. As however, it has appeared in practice that these 40 apparatuses are not without danger, they are not allowed to be used or only when several precautions have been taken. Further these apparatuses have not yet been constructed for larger capacities.

45 According to the invention an apparatus is provided which may be constructed for any capacity whilst it may be worked without risk.

The apparatus according to the invention 50 consists in the first place of tubes and the like through which the liquid flows and in each tube is provided a heating wire of the heating winding.

According to the invention each tube may 55 be provided with an insulating coating or

cover e. g. a glass tube, fixedly secured thereto.

Further the heating winding may be according to the invention consist of bare preferably spirally wound wires each of which are connected with one end to a separate current supply and with the other end are connected together to a starpoint.

Further according to the invention a heating wire may be connected to a contact 65 which is arranged in a block of insulating material, which is fixedly secured to the apparatus and which preferably extends into the insulating cover or coating of the 70 accessory tube.

The apparatus may further be surrounded by a heat insulating casing in such a manner that the temperature of the heated liquid in the apparatus decreases only slowly.

As the wires immediately communicate 75 the heat to the liquid no losses occur and the liquid is very quickly brought to the desired temperature, whilst on account of the special constructive embodiment of the insulating blocks which extend into the glass 80 tube no electrolysis can occur. As moreover the heating winding consists of clean wires which are all arranged separately eventual disturbances may soon be found 85 and repaired.

An embodiment of the invention is shown in the accompanying drawings.

Fig. 1 is a front view of an apparatus according to the invention, partially in cross section.

Fig. 2 shows a top view of the apparatus according to Fig. 1.

Fig. 3 shows a bottom view of the apparatus over the line III-III in Fig. 1.

By 1 are preferably indicated the brass 95 water conduits which are secured in the head piece 2 and the foot piece 3. Each tube is provided with an insulating coating, in the example a glass tube 4, which by means of nipples with outerthread 5 are 100 secured in the headpiece 2 and the footpiece 3. A watertight connection is obtained by means of packing inserted between said nipples 5 and the tube 1, so that no liquid can pass between the glass tube 4 and the tube 1. 105

In the cover 6 of the head piece 2 holes are provided for locating the blocks 7 of insulating material wherein are the contact-terminals 8. These blocks 7 are provided with a shoulder 9 which rests on the ledge 110

- 10 of the holes. A packing ring is laid between the shoulder 9 and the ledge 10, so that by means of a nipple with outerthread 11 a watertight connection is obtained.
- 5 Through the blocks 7 is a through conductor 12 to which the heating wire 13 which is preferably wound spirally is secured in any suitable manner. These blocks extend into the glass tubes 4, thereby preventing the
- 10 occurrence of electrolysis when using the apparatus. The cover 6 is attached to the headpiece 2 by means of screws 14. Further the headpiece possesses two terminals 15 for coupling a second heating apparatus and
- 15 for connecting the tube to the drycock. By means of a double nipple with a left and a right thread these connections may be established in a simple manner. The heating wires 13 lead through the tubes 1 and 4
- 20 downward and are here in the footpiece 3 connected in a starpoint by means of a bridge piece 16. The footpiece 3 is adapted to be shut off by a cover 17. Also this footpiece 3 possesses two terminals 18.
- 25 Further the apparatus may be enclosed in a casing 19 which casing is indicated in Fig. 1 with dot-dash-lines. This casing may be covered with cork, slag-wool or the like, so that rapid cooling of the water which is
- 30 in the apparatus is prevented.
- Having now particularly described and ascertained the nature of my said invention and in what manner the same is to be performed I declare, that what I claim is:
- 35 1. An electric heating apparatus for liquids, comprising a plurality of tubes ar-

ranged side by side and forming the sole conduit for the passage of the liquid, means for connecting the said tubes with each other, an insulating layer coating each tube, 40 a heating element having an exposed heating wire located in each tube, said heating wires being connected at one end to the current supply means and being connected at the other ends in a starpoint. 45

2. An electric heating apparatus for liquids, comprising a plurality of tubes arranged side by side and forming the sole conduit for the flow of liquid, a glass tube mounted in each of said conduit tubes and forming the 50 passage for the liquid, a heating element having one exposed heating wire in each glass tube, said heating wires being connected at one end to current supply means and being connected at the other ends in a 55 starpoint.

3. An electric heating apparatus for liquids according to claim 1, comprising a contact secured to each of said wires, a block of insulating material carrying said contact 60 and extending into the tube, each heating wire being wound spirally within said tube.

4. An electric heating apparatus for liquids according to claim 1, comprising at least two inlet connections for the liquid 65 and at least two outlet connections for the liquid, to permit the connection of a plurality of apparatus.

In testimony whereof I affix my signature.

KAREL FREDERIK HENNEMAN.
